UNITED STATES PATENT OFFICE.

ALBERT BREST, OF NEWCASTLE, PENNSYLVANIA.

FURNACE CLEANER.

Application filed April 11, 1928. Serial No. 269,280.

This invention relates to means for cleaning the radiator of a furnace, the general object of the invention being to provide a rotary member on the bottom of the radiator for collecting the soot and dust, with means for rotating the same and with a spiral associated with the rotary means for scraping the soot and dust from the rotary member and either forcing it into the opening in the dome of the radiator so that it will drop into the furnace or for moving the soot and dust into the clean-out opening in the furnace.

Another object of the invention is to provide a deflector member arranged alongside the spiral which helps the spiral to remove the material from the rotary member, with means for reversing the parts to place the deflector member on either side of the spiral.

Another object of the invention is to so form the parts that they can be placed in position through the clean-out opening and removed therefrom, with means for detachably holding the spiral supporting member in the clean-out opening.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which—

Figure 1 is an elevation with parts in section, of a furnace, showing the invention in use.

Figure 2 is a section on line 2—2 of Figure 1.

Figure 3 is a front end view of the invention.

Figure 4 is a rear end view thereof.

Figure 5 is a section on line 5—5 of Figure 3.

Figure 6 is a fragmentary view of the rotary member, showing the means for connecting the sections thereof together.

Figure 7 is a section on line 7—7 of Figure 6.

As shown in these views, I place a ring-shaped plate 1 in the lower part of the annular member of the radiator A of the

furnace, this plate being formed of sections, with each section detachably connected to the other section by a screw 2 in one section engaging a keyhole-shaped opening 3 in the adjacent section. The sections must be so formed that they can be passed through the clean-out opening B of the furnace so that they can be readily put in place in the radiator or removed therefrom. The outer periphery of the plate is formed with the teeth 4. A cylindrical member 5 has a cross piece 6 at its front end in which is journaled the stem 7 of a screw or spiral 8 so that the spiral is rotatably supported by the member 5. The outer end of the stem 7 is shaped to receive a crank handle so that the spiral can be rotated.

The member 5 is removably held in the clean-out opening B by the plates 9 attached to its sides and frictionally engaging the walls of the clean-out opening and by the set screw 10 threaded into a hole in the top of the member 5 and engaging the top wall of the clean-out opening, this screw 10 acting to hold the member 5 against the bottom of the clean-out opening. The bottom part of the member 5 is provided with a threaded hole 11 so that it can be reversed and the screw 10 placed in this hole 11 when the spiral is to be turned in an opposite direction. When the member 5 is properly positioned in the clean-out opening, the spiral will rest on the rotary plate 5 and a gear 12 is fastened to the spiral an appreciable distance from its front end, the teeth of the gear engaging the teeth 4 of the plate so that when the spiral is rotated, the gear 12 will impart rotary movement to the plate 1.

A deflector plate 13 of curved shape in cross section is fastened to the member 5 and parallels the spiral, this deflector plate preventing ashes, dust, soot or the like from being carried around by the plate 1 and causing such material to be moved off the plate by the spiral. When the opening 14 in the dome or central portion 15 of the radiator is opposite the clean-out opening, the parts are preferably positioned so that when the spiral is turned to the left, the material on the plate 1 will be pushed by the spiral through said opening 14 into the furnace, it being understood that the member 13 is on the right hand side of the spiral when the spiral is being so moved. Thus as the spiral is revolved, the plate 1

will be rotated so that the material on said plate will be scraped therefrom by the spiral and the deflector 13 and forced through the opening 14 into the furnace. 5 In radiators where the opening 14 is not opposite the clean-out opening, the member 5 is reversed and the screw 10 placed in the hole 11 so that said screw will hold the member 5 in this reverse position. Then the 10 deflector 13 will be on the left hand side of the spiral so that when the spiral is turned to the right, the material on the plate will be forced through the clean-out opening. Of course, the material can be forced 15 through either the opening 14 or the clean-out opening as desired, it simply being necessary to properly position the spiral and the deflector 13 to secure the desired action.

20 It is thought from the foregoing description that the advantages and novel features of my invention will be readily apparent.

It is to be understood that I may make changes in the construction and in the combination and arrangement of the several parts, provided that such changes fall within the scope of the appended claims.

What I claim is:—

1. A device for cleaning a radiator of a furnace comprising a ring-shaped plate placed in the annular chamber of the radiator and rotatably supported therein, a supporting member removably held in the clean-out opening of the furnace, a spiral rotatably supported by said member and extending over the plate and adapted to remove the material from the plate means for rotating the spiral and the plate and a deflector member supported by the supporting member and contacting with a portion of the spiral.

2. A device for cleaning a radiator of a furnace comprising a ring-shaped plate placed in the annular chamber of the radiator and rotatably supported therein, a supporting member removably held in the clean-out opening of the furnace, a spiral rotatably supported by said member and extending over the plate and adapted to remove the

material from the plate, means for rotating 50 the spiral and the plate, a deflector member supported by the supporting member and contacting with a portion of the spiral, said ring-shaped plate being formed in sections which are detachably connected together, 55 the sections being shaped so that they can pass through the clean-out opening.

3. Means for removing foreign matter from the radiator of a furnace comprising a sectional ring-shaped plate rotatably mounted in the annular chamber of the radiator, teeth on the periphery of the plate, a cylindrical member, a spiral rotatably supported thereby, means for removably holding the cylindrical member in the clean-out 60 opening of the furnace, said spiral extending across the plate and contacting therewith for removing material from the plate, a gear fastened to the spiral and engaging the teeth on the plate for imparting movement 65 to the plate when the spiral is rotated and a deflector member of curved shape in cross section attached to the cylindrical member and contacting the inner portion of the spiral.

4. Means for removing foreign matter from the radiator of a furnace comprising a sectional ring-shaped plate rotatably mounted in the annular chamber of the radiator, teeth on the periphery of the plate, a cylindrical member, a spiral rotatably supported thereby, means for removably holding the cylindrical member in the clean-out opening 70 of the furnace, said spiral extending across the plate and contacting therewith for removing material from the plate, a gear fastened to the spiral and engaging the teeth on the plate for imparting movement to the plate when the spiral is rotated, a deflector member of curved shape in cross section 75 attached to the cylindrical member and contacting the inner portion of the spiral and means for permitting the cylindrical member to be reversed in the clean-out opening 80 whereby the deflector member can be placed 85 on either side of the spiral.

In testimony whereof I affix my signature.
ALBERT BREST.
